(57) **CLAIM**

The ornamental design for a refrigerated cooler, as shown and described.

DESCRIPTION

FIG. 1 is an elevated perspective front view of the of the refrigerated cooler with the shape of the border of the front window in the display cabinet indicated in dashed line as environmental, the top doors, door tracks and door framing of the cooler indicated in dashed line as environmental, the pivot bolt near the bottom, rear side edge of the display cabinet and the locking pin near the top, rear side edge of the display cabinet indicated in dashed line as environmental, and the base of the cooler indicated in dashed line as environmental;

FIG. 2 is a top plan view of an embodiment as in FIG. 1 with the top doors, door tracks and door framing of the cooler indicated in dashed line as environmental and the pivot bolts near the bottom, rear side edges of the display cabinet indicated in dashed line as environmental;

FIG. 3 is a bottom plan view of an embodiment as in FIG. 1 with the base of the cooler and the pivot bolts near the bottom, rear side edges of the display cabinet indicated in dashed line as environmental;

FIG. 4 is a left side plan view of an embodiment as in FIG. 1 with the base of the cooler, the pivot bolt near the bottom, rear side edge of the display cabinet, and the locking pin near the top, rear side edge of the display cabinet indicated in dashed line as environmental;

FIG. 5 is a right side plan view of the design of FIG. 1 with the base of the cooler, the pivot bolt near the bottom, rear side edge of the display cabinet, and the locking pin near the top, rear side edge of the display cabinet indicated in dashed line as environmental;

FIG. 6 is a rear plan view of an embodiment as in FIG. 1 with the base of the cooler and the pivot bolts near the bottom, rear side edges of the display cabinet indicated in dashed line as environmental; and,

FIG. 7 is a front plan view of an embodiment as in FIG. 1 with the shape of the border of the front window in the display cabinet indicated in dashed line as environmental, the base of the cooler indicated in dashed line as environmental, and the pivot bolts near the bottom side edges of the display cabinet indicated in dashed line as environmental.
